UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

ANTIFRICTION BEARING.

Application filed January 16, 1926. Serial No. 81,647.

This invention relates to anti-friction bearings.

One object of this invention is to provide an anti-friction bearing especially adapted 5 for use as a side bearing on railway cars, and wherein the parts are so arranged that the anti-friction element will be returned to normal position automatically when the load is released therefrom.

10 A more specific object of the invention is to provide a side bearing of the above character, in which the anti-friction element may be in the form of a plain steel cylindrical roller, in conjunction with centering mechanism for said roller, including transversely disposed resilient units arranged at each end of the roller housing, together with connecting means arranged to simultaneously flex or actuate all of said resilient means upon 15 movement of the roller to either one, or the other side of central position with reference to the roller housing.

Other and further objects of the invention will more clearly appear from the description and claims hereinafter following.

20 In the drawings, Figure 1 is a vertical, longitudinal sectional view of the invention, partly in elevation, showing the same secured in position upon the truck bolster. Figure 2 is a horizontal, sectional view of the invention substantially upon the line 2-2 of Figure 1; Figure 3 is a fragmentary vertical, longitudinal, sectional view, partly in elevation, of a slightly different embodiment of the invention. And Fig. 4 is a horizontal, sectional view of the invention as illustrated in Fig. 3, showing one half only of the bearing, substantially upon the line 4-4 of Fig. 3.

25 The invention broadly comprises a housing A; an anti-friction element B; resilient means C; transmitting elements D; and coupling elements E.

30 Referring first to Figs. 1 and 2, the housing A comprises a rectangular casting having side walls 5 and end walls 6 and 7, each side wall being provided with longitudinally spaced offsets adjacent the top edge thereof, providing two horizontally extending elongated chambers or recesses 8 at each side of 35 the housing for a purpose hereinafter described, each side wall also being provided with top, over-hanging flanges as indicated at 9. The end walls 6 and 7 diverge outwardly as shown, are then curved inwardly as indicated at 10, and extend inwardly to provide

overhanging top walls 11 which merge with the overhanging flanges upon the side walls, the inner edges of the overhanging top walls being curved as indicated at 12, said walls being utilized as stops for the roller B to 40 limit its movement to either side of central position. The bottom edges of the end walls 6 and 7 are provided with outwardly extending flanges 13-13, which rest upon a bearing plate 14, forming the bottom of the housing, 45 the flanges 13-13 being secured to the bearing plate by suitable means, such as rivets 15-15, extending through the flanges and bearing plate. The side walls 5 of the housing are extended slightly below the top surface of the bearing plate as indicated at 16. The bearing plate 14 is preferably of hardened steel and is of a width adapted to fit between the side walls 5 of the housing. The bearing plate 14 extends outwardly beyond 50 the flanges 13, the outer ends of the bearing plate being secured to the top plate of the truck bolster 17, by rivets or other suitable means.

55 The anti-friction element B is in the form of a plain cylindrical roller, which may be a section cut off of a round steel bar, and hence is of minimum cost since it is not necessary to cast the same. Said roller is disposed in the housing, and is adapted to roll back and forth on the bearing plate 14, the width of the roller being somewhat less than the width between the walls 5-5 of the housing as shown in Fig. 2.

60 The centering means include the resilient 60 means C comprising transversely disposed helical springs 18 and 19, one being arranged in each end of the housing, each spring being of a length so as to extend across the housing and having its opposite ends disposed in the elongated chambers or recesses 8 provided therefor in the side walls of the housing, the ends of each spring being loosely disposed in said chambers so as to move laterally therein during operation of the bearing.

65 The transmitting elements D-D are two in number, and disposed at each side of the roller B. Each transmitting element D is in the form of a hollow, cylindrical member having a central bore 20 extending therethrough, through which the related helical spring extends, the wall of the bore in each of the transmitting elements being curved longitudinally, the parts of said wall most closely approaching at the center of the mem- 70

ber and diverging outwardly toward its ends, the wall at the point of closest approach of the annular surfaces of the wall of the bore providing an opening slightly larger than 5 the helical spring extending therethrough. Each transmitting member is preferably of a length approximately the same as the width of the anti-friction element B, the member in each instance being carried by the spring 10 with which it is associated. The elements D—D are adapted to bear upon the roller B, and the engaging faces thereof are curved as indicated at 21 to conform to the shape of the roller, said curved faces extending above 15 the center of the roller B, and serving to maintain the same within the housing.

The connecting or coupling elements E—E are two in number, one of the same being disposed upon each side of the roller B, each 20 element E being in the form of a flat link 22, the opposite ends of which are provided with circular openings 23 and 24 through which the ends of the springs 18 and 19 extend, the links connecting the ends of the two springs 25 in series, so that the same may be operated simultaneously. The length of the links is such that when the roller B is in central position the ends of the springs 18 and 19 engage the inner limits of the recesses 8 in the 30 side walls of the housing.

In operation, assuming the anti-friction element to be moving toward the right, as indicated in dotted lines in Fig. 1, the transmitting member D in the path of the roller B 35 will be moved toward the end wall 7, engaging the spring 19 intermediate its ends, and substantially in a direction perpendicular to the longitudinal extent of said spring, causing longitudinal flexing of said spring, and by 40 reason of the connection of the ends of said spring 19 with the ends of the spring 18 at the opposite end of said housing by the coupling members 22, said latter spring also will be simultaneously flexed reducing the total 45 necessary for each, and when load is removed from the roller, the same is returned to and held in central position by the simultaneous movement of the springs 18 and 19. Of course movement of the anti-friction roller B 50 toward the left also will result in combined flexing of the transversely disposed springs. In this manner the combined force of the springs is utilized for returning the anti-friction roller to and maintaining the same in 55 central position.

Referring now to Figs. 3 and 4, a slightly different embodiment of the invention is illustrated. This construction includes a housing A'; an anti-friction roller B'; transmitting elements C'; resilient means D' and coupling elements E'.

In this construction the housing A' is of box-like form generally similar to the housing A heretofore described, except that the 60 end walls 50 thereof are disposed in substan-

tially parallel relation instead of diverging outwardly, the extensions 51 upon the end walls providing overhanging parts which act as stops for the roller as indicated at 51. The roller B' is of the same construction as 70 the roller B, heretofore described.

The transmitting elements C' are two in number and disposed upon either side of the anti-friction element B' at opposite ends of the housing, the bottom portions 52 of said 75 transmitting members resting upon the bearing plate 53 forming the bottom of the housing. Each transmitting element C' comprises a transversely arranged follower member, the inner face of which is curved to conform 80 to the surface of the roller B', and the opposite ends of which are adapted to abut against stops 54 formed on the side walls of the housing to limit the movement of the follower member in the direction of the roller. The rear surface of the follower is provided with horizontally disposed ribs 55, which are longitudinally bowed outwardly as shown in Fig. 4, the upper and lower ribs 55 being inwardly offset as indicated at 56 to accommodate a flat plate spring 56^a, which is disposed transversely across the end of the housing. The transmitting element and the spring, at the opposite end of the housing, are of identically similar construction to 95 those just described, except for their opposite disposition, and will be designated by the same reference characters.

The coupling elements E'—E' are two in number, one of the same being disposed upon 100 each side of the housing, each coupling element being in the form of an elongated link, having inwardly turned engaging portions 58 at its opposite ends, which are adapted to fit against the outer surfaces of the opposite 105 ends of each plate spring 56^a, the coupling elements being arranged to slide in the guideways 59 formed in each side wall of the housing, when the bearing is operated.

In operation, assuming the roller B' to be 110 moving in a direction toward the right, as shown in dotted lines in Fig. 3, the follower C' in the path of the roller is carried therewith, while the follower C' at the opposite end of the housing is held stationary by engagement with stops 54. Movement of the right hand follower causes the same to bear against the right hand spring 56^a intermediate its ends, said ends of its springs being yieldably restrained against movement by 115 the inturned ends 58 of the elements E'—E', resulting in bowing of the right hand spring in conformance with the curved surfaces of the ribs 55 of the right hand follower. During this action the coupling elements E—E, 120 which have the inturned portions of their opposite ends engaging the plate spring at the left hand of the housing, serve to flex the left hand plate spring against the left hand follower which is held against the stops 54, 125 130

so that both of the plate springs 56^a are simultaneously flexed and in series, each one giving half of total action, the energy stored in said springs serving to return the roller 5 B' to, and maintain the same in central position. Movement of the anti-friction element B' in the opposite direction also simultaneously flexes both springs 56^a due to an action similar to that just described.

10 While I have herein shown and described what I now consider the preferred manner of carrying out my invention, the same is merely illustrative, and I contemplate all changes and modifications that come within 15 the scope of the claims appended hereto.

I claim:

1. In a side bearing of the character described, the combination with a mounting including a bearing plate; of an anti-friction element movable back and forth on said bearing plate; elongated flexible resilient members disposed upon opposite sides of said anti-friction element in the direction of movement thereof, and extending transversely of 25 the path of movement of said element and means actuated by said element for flexing all of said resilient members upon movement of said anti-friction element to one side or the other of central position.

30 2. In an anti-friction side bearing, the combination with a mounting including a bearing plate; of an anti-friction element movable back and forth on said bearing plate; and means for centering said element and 35 yieldingly opposing movement thereof, including elongated flexible resilient members disposed in the path of said element, said element being interposed between said members, and said members extending substantially 40 transversely of the direction of movement of said element; and means for restraining movement of the ends of said member to compel said flexing of said member upon movement of said anti-friction element from 45 centered position.

3. An anti-friction bearing including a mounting and an anti-friction element movable longitudinally to and fro on said mounting; of spaced elongated resilient flexible 50 members disposed on opposite sides of said element and having their longitudinal dimensions arranged transversely of the path of movement of said element; means for restraining bodily movement of said members; 55 and means actuated by said anti-friction element when moved from centered position for flexing said resilient members.

4. An anti-friction bearing, including a mounting and an anti-friction roller movable longitudinally on said mounting; of spaced elongated flexible resilient means disposed on opposite sides of said element and arranged across the path of said element; and means actuated by said anti-friction element for flexing all of said resilient means

when moved to one side or the other of central position with respect to said mounting.

5. In a device of the character described, the combination with a mounting; of an anti-friction element movable to and fro on said mounting; elongated resilient flexible means disposed across the path of said element; means restraining movement of the end portions of said resilient means; and transmitting means arranged between said anti-friction element and said resilient means, said transmitting means being provided with curved faces adapted to engage said resilient means to flex the same upon movement imparted thereto by said anti-friction element from centered position.

6. An anti-friction bearing comprising a mounting; an anti-friction element movable longitudinally of said mounting; independent, spaced elongated spring means arranged at either side of said anti-friction element and having their longitudinal dimensions extending transversely of the path of movement thereof; means associated with said mounting for limiting the movements of the end portions, of one of said spring means in one direction and the other spring means in the opposite direction; and devices for coupling said spring means to effect flexing of both of the same upon movement of said roller in either one direction or the other.

7. An anti-friction bearing, comprising a mounting; an anti-friction element movable longitudinally of said mounting; spaced independent elongated resilient flexible members arranged at either side of said anti-friction element; means associated with said mounting for limiting the movement of the end portions of said resilient members; devices for coupling said resilient members whereby all of the same are operated upon movement of said anti-friction element in either direction; and transmitting means interposed between said resilient members and said anti-friction element, said transmitting means being provided with curved faces adapted for engagement with the resilient members between the end portions thereof.

8. In an anti-friction bearing, the combination with a mounting having a bearing surface; of an anti-friction element movable back and forth on said bearing surface; a follower at each side of said element, each follower having a curved face conforming to the periphery of said element; and resilient flexible means having its longitudinal dimensions extending transversely of the path of movement of said element and bearing on said followers to urge the same toward each other and said element.

9. In an anti-friction bearing of the character described, comprising a housing having side and end walls and open at its bottom, each of said side walls being provided with spaced elongated recesses; coil springs dis-

posed transversely of said housing, each of said springs having the opposite end portions thereof disposed in said recesses; followers mounted on said coil spring, each of said 5 followers having curved engaging faces co-operating with said springs; a bearing plate and an anti-friction roller inserted through the open bottom of said housing, said anti-

friction roller being disposed between said followers and extending outwardly of the 10 top of said housing, said housing being secured to said bearing plate.

In witness that I claim the foregoing I have hereunto subscribed my name this 8th day of January 1926.

JOHN F. O'CONNOR.
